CLOTHESPOLE

Ersyl F. Chambliss, Chicago, Ill., assignor of one-half to Joseph W. Fay, Villa Park, Ill.

Application November 22, 1934, Serial No. 754,329

5 Claims. (Cl. 211—123)

My invention relates to clothes-poles such as are arranged across clothes closets from one wall to another and attached at opposite ends to the molding strips or cleats with which the walls of the closet are provided.

Extensible devices of this character for employment in closets of varied widths have been provided before, but the mountings for these devices either have not provided the requisite strength or have been difficult to attach, or, when attached, were impossible to remove without mutilating or destroying the attachment means.

The object of my present invention is to provide an extensible device of the character above described with improved means for attaching the ends of the device to the molding strips or cleats with which the walls of the closet are provided, which improved means will provide attachments of requisite strength and attachments which may be readily applied, and at the same time are adapted to be readily removed without mutilating or destroying the attachment means or pole.

Further objects and the features and advantages of the invention will be apparent from the following detailed description taken in connection with the accompanying drawing, in which:

Figure 1 is a perspective view of a device embodying the present invention showing fragmentarily at one end a section of one of the closet walls supporting one end of the device;

Figure 2 is a vertical section taken on the line 2—2 of Figure 1, but showing the adjacent end of the device attached to the molding strip or cleat with which the adjacent wall of the closet is provided;

Figure 3 is an end view showing the mounting of the attachment means upon the ends of the pole; and

Figure 4 is a horizontal section taken on the line 4—4 of Figure 1.

In the illustrated embodiment of the invention, 5—5 designate the opposite walls of a closet; 6—6 supporting strips, such as molding or hook-strips secured to the walls; and 7 the improved 45 extensible clothes-pole.

The pole 7 is shown as comprising telescopically related sections in the form of tubes 8 and 9 equipped with means 10 and 11, respectively, for attaching the ends of the pole to the supporting 50 strips 6, 6. The attaching means at 10 and 11 are of the same form and are applied to the tubular members 8 and 9 in the same manner, so that a description of one will suffice for both.

Describing the attachment means at 10, it 55 consists of a sheet metal bracket member 12 de-

pressed at 13 to receive the adjacent ends of the tube 8 which has integral tabs 13' extending through diametrically opposite arcuate openings 14 in the bracket member 12, and turned over and clinched firmly to the bracket member to 5 secure this member rigidly to the adjacent end of the tube 8. It is to be understood that the invention may employ other means than the means shown for rigidly securing the outer ends of the tubes 8 and 9 to the respective bracket 10 members 12. The opposite end of the outer tube 8 may be finished by means of a ferrule 15.

The flanges at the opposite vertical edges of the bracket member 12 are turned to form channels 16, and a second sheet metal bracket member 17 is slidable in these flanges for adjusting the attachment means to molding or hook-strips of different widths. The upper end of the bracket member 12 is turned in at 18 and the lower end of the bracket member 17 is turned in at 19 to 20 embrace the upper and lower edges of the molding or hook-strips. These inturned flanges 18 and 19 have tongues 20 and 21 turned downwardly and upwardly, respectively, from the flanges 18 and 19, and adapted for firm biting engagement 25 with the upper and lower edges of the molding or hook-strips 6.

The bracket members 12 and 17 are adjustably connected by a screw or bolt 22, the shank of which passes through openings in the flanges 18 30 and 19 and engages beneath the flange 19 in a wing nut 23. Adjacent its upper headed end, the bolt 22 has a square or non-circular neck 24 which holds the bolt against turning in the flange 18. 35

In applying the pole, the bracket members 12, 17, at opposite ends thereof, are opened sufficiently to engage the flanges 18 and 19 over the molding or hook-strips 6, whereupon the pole sections 8 and 9 are extended between the strips 6, and the 40 flanges 18 and 19 of the bracket members are engaged over the strips. The wing nuts 23 are then tightened to clamp the brackets to the respective strips 6 and to force the tongues 20 and 21 firmly into biting engagement with the opposite edges 45 of the wood strips, as shown. The disposition and adjustment of the bracket members 12, 17, substantially normal to the axis of the pole 7, with their radial extension from opposite sides of the pole, provides a strong attachment which can 50 be conveniently applied and removed, and the biting engagement of the tongues 20 and 21 with the opposite edges of the molding or hook-strips 6 further increases the security of the attachment. 55

I do not intend to be limited to the precise details shown or described.

I claim:

5. 1. An extensible clothes-pole comprising telescoping pole sections, bracket members rigidly secured to the outer ends of said sections, second bracket members slidably adjustable in said first bracket members, said first and second bracket members being disposed and adjustable substantially normal to the axis of the pole and extending radially from opposite sides of the pole, in-turned flanges at the upper and lower ends, respectively, of said bracket members, and bolts passing through said flanges and engaging in cooperating nut members for clamping the flanges to the upper and lower edges of a molding strip. 10
10. 2. An extensible clothes-pole comprising telescoping pole sections, bracket members rigidly secured to the outer ends of said sections, second bracket members slidably adjustable in said first bracket members, said first and second bracket members being disposed and adjustable substantially normal to the axis of the pole and extending radially from opposite sides of the pole, in-turned flanges at the upper and lower ends, respectively, of said bracket members, and bolts passing through said flanges and engaging in cooperating nut members for clamping the flanges to the upper and lower edges of a molding strip. 15
15. 3. An extensible clothes-pole comprising telescoping sections, bracket members rigidly secured to the outer ends of said sections, said bracket members having depressions for receiving the ends of the pole sections, tabs integral with the ends of said sections and extending through openings in said bracket members and turned over and clinched to said bracket members, the opposite vertical edges of said bracket members being turned to form channels, second bracket members slidable in said channels, said first and second bracket members being disposed and adjust- 20
20. able substantially normal to the axis of the pole and extending radially from opposite sides of the pole, in-turned flanges at the upper and lower ends, respectively, of said bracket members, bolts passing through said flanges and engaging in cooperating nut members for clamping the flanges to the upper and lower edges of a molding strip, and tongues turned downwardly and upwardly from the respective flanges and adapted for biting engagement with the upper and lower edges of the molding strip. 25
25. 4. An extensible clothes-pole comprising telescoping pole sections, bracket members rigidly secured to the outer ends of said sections, second bracket members slidably adjustable in said first bracket members, said first and second bracket members being disposed and adjustable substantially normal to the axis of the pole and extending radially from opposite sides of the pole, in-turned flanges at the upper and lower ends, respectively, of said bracket members, and adjustable clamping means secured to said bracket members and engaging the in-turned flanges thereof for clamping said in-turned flanges to a molding strip. 30
30. 5. An extensible clothes-pole comprising telescoping pole sections, bracket members rigidly secured to the outer ends of said sections, second bracket members slidably adjustable in said first bracket members, said first and second bracket members being disposed and adjustable substantially normal to the axis of the pole and extending radially from opposite sides of the pole, in-turned flanges at the upper and lower ends, respectively, of said bracket members, and adjustable clamping means secured to said bracket members and engaging the in-turned flanges thereof for clamping said in-turned flanges to a molding strip. 35
35. 40. 45. ERSYL F. CHAMBLESS. 45
